UNITED STATES PATENT OFFICE.

STANTON GRIFFITH, OF BELOIT, WISCONSIN.

MOLDING-MACHINE.

No. 798,897.

Specification of Letters Patent.

Patented Sept. 5, 1905.

Application filed November 18, 1904. Serial No. 233,372.

To all whom it may concern:

Be it known that I, STANTON GRIFFITH, a citizen of the United States of America, residing at Beloit, in the county of Rock and State 5 of Wisconsin, have invented certain new and useful Improvements in Molding-Machines, of which the following is a specification.

This invention relates to a molding-machine. Its object is to provide a machine of that class 10 which shall be of simple and comparatively inexpensive construction and withal highly efficient in operation; and it consists in the features of construction and combinations of parts hereinafter fully set forth and of the 15 novel features thereof specifically pointed out in the claims appended to this specification.

Referring to the accompanying drawings, which form a part of this specification, Figure 1 is a top plan view of a machine embodying 20 my invention with the drag removed therefrom. Fig. 2 is a like view of the same with the drag and core-box removed therefrom and their supporting-standards sectioned away. Fig. 2^a is a section at the dotted line 2^a 2^a in 25 Fig. 2 of parts there shown. Fig. 3 is a partial section, at the dotted line 3 3 in Fig. 1, of the machine with its drag and core-box. Fig. 4 is a section at the dotted line 4 in Fig. 3 of parts there shown. Fig. 5 is a section at the 30 dotted line 5 in Fig. 3 of parts there shown. Fig. 6 is a central vertical section of the drag and core-box of the machine in positions the reverse of those shown in Fig. 3, the drag being shown supporting and withdrawing a core 35 from its box. Fig. 7 is a central vertical section of a cope, pattern, and stripping-plate of the machine, the pattern being shown descending out of the cope and below the stripping-plate. Fig. 8 is a section at the dotted 40 line 8 8 in Fig. 7 of parts there shown. Fig. 9 is a central vertical section of a flask made up of the drag and cope shown in Figs. 6 and 7 and containing a complete mold ready to receive molten metal.

Like letters of reference indicate corresponding parts throughout the several views.

A is the base of the machine and is provided with upwardly-projecting tongues A', bearing-lugs A², and two pairs of substantially 50 parallel slots A³, all serving purposes to be explained hereinafter.

B represents vertical standards having grooves B', Fig. 3, in the lower ends thereof to admit the counterpart tongues A' on the

base A and provided at their upper end portions with shaft-bearings B² and lug-bearings B⁴. 55

B³ represents threaded rods mounted in correspondingly-threaded bearings B⁴ in the lugs A² and inserted through and maintained in 60 bearings B⁵ in the standards B by means of fast collars B⁶.

B⁷ represents cranks for rotating the threaded rods B³, wherethrough the standards B may be adjusted toward or from each other 65 any desired distance within the limits of the mechanism, the scales " on the tongues A' serving as guides for the adjustment of such standards B and the bolts and nuts B⁸ B⁹ serving as means for securing them to their 70 base A after adjustment.

C, Fig. 3, is a pit located below the central portion of the base A of the machine.

C' is a cylinder vertically seated on a bearing in the bottom of the pit C and projecting 75 upward through the base A of the machine.

C², Figs. 6 and 7, is a piston slidably mounted in the cylinder C' and provided at its upper end with a horizontal platen C³.

C⁴ represents guide-rods rigidly secured by 80 their upper ends to the platen or platen-support and projecting downward therefrom through openings C⁵ in the machine-base A into the pit C.

C⁶ represents springs encircling and resting 85 upon bearings C⁷ on the guide-rods C⁴ and serving as cushions for the platen C³ as it approaches its upper limit of travel.

C⁸ is an air-pipe tapped into the lower portion of the cylinder C'. The platen C³ may 90 be driven upward by means of compressed air admitted into the cylinder C' through the pipe C⁸, the operation of gravity normally sustaining it in the position shown in Fig. 3. The cylinder C' exhausts through a valve there- 95 in. (Not shown.)

D represents tracks, preferably fast to the standards B, supported by means of feet D' and extending from the machine to the east- 100 ing-floor of the foundry.

E is a laterally-extensible skeleton truck provided with rollers E' for its support and propulsion on the tracks D. The truck may be rendered laterally extensible by employing coöoperating slidably-connected members 105 b⁹ b¹⁰.

The bearings B², Fig. 4, in the upper ends of the standards B are provided with caps b,

hinge-jointed thereto by means of lugs b' and pintles b'' . The bearings B^2 and caps b are also recessed at $b^3 b^4$ to admit a bolt b^5 , which is pivoted by its lower end to the part B^2 by means of a pintle b^6 . Whenever it is desired to uncover the bearing B^2 , the nut b^7 should be loosened and the bolt b^5 be swung out of the recess b^3 in the cap b .

F is a core-box provided with transverse opposite trunnions F' , whereby to rotatably mount the same in the bearings B^2 in the standards B . The core-box F may be of any practicable form and of any desired dimensions within the limits of the machine, its supporting-standards B being adjustable laterally and provided with bearings B^2 , adapted to admit trunnions of any core-box when they are of uniform diameter.

F^2 , Fig. 1, is a crank for turning the core-box B in its bearings B^2 .

G is a drag adapted to be used in conjunction with the core-box F to form and support the male portion of a mold. The drag G may be of any practicable form and size usable with a core-box of the class represented by the above-described core-box F .

H , Figs. 7 and 8, is a pattern of any practicable form usable in connection with the hereinbefore-described devices.

I is a stripping-plate usable with any practicable form of a mold. Pins I^1 may be inserted through openings I^2 in the standards B into sockets I^3 in the stripping-plate I to secure the same onto its supporting-lugs B^a on the standards B .

J is a cope of any practicable form usable in connection with the stripping-plate I and drag G . The cope J is provided with transverse opposite lugs J' , whereby to connect lifting mechanism therewith.

K represents clamps provided with thumb-screws K' for temporarily securing the drag-board K^2 , drag G , and box F together.

The operation of the machine to produce a complete mold, like that shown in Fig. 9, for instance, will be as follows: The core-box F and drag G , being in the relations and positions shown in Fig. 3, are first rammed full of sand, which is then struck off even with the free end of the drag, and a drag-board K^2 is placed and secured thereon by means of the clamps K . The positions of the core-box and drag are then reversed. Compressed air is next admitted to the cylinder C' and there-through elevates the platen C^3 until it contacts the drag-board K^2 . The clamps K are next removed, and the compressed air being shut off from the pipe C^8 gravity and the weight of the drag G and core X , Fig. 6, will cause the platen C^3 to descend to the position shown in Fig. 3, the platen depositing the drag G , with the core X , on the truck E , Fig. 6, as it passes downward therethrough. The

truck E is then pushed along the tracks D any desired distance, and the drag G , with the core X , is then lifted therefrom and deposited on the casting-floor, as at Fig. 9. Obviously any desired number of cores X may be formed in drags G and transferred from the machine to the casting-floor in the manner described above. The core-box F is detached from its bearings B^2 when the desired number of cores X have been made, and a stripping-plate I , Fig. 7, is then mounted and secured on the bearings B^a on the standards B . The pattern H is next placed on the platen C^3 , and the latter is elevated, in the manner already described, to the position indicated by dotted lines α in Fig. 7. The cope J is then placed in position on the stripping-plate I and is thereafter rammed full of sand around the pattern H . The platen C^3 is then caused to descend, and thereby withdraw the pattern H from the female portion X' of the mold. The cope J is next conveyed to the casting-floor and placed in position upon the drag G , Fig. 9. The operation just described is continued with additional copies until they correspond in number with their drags.

Having fully described my invention, what I claim as new, and desire to secure by Letters Patent, is—

1. In combination, a main supporting-base, a pair of vertical standards laterally adjustable thereon, a core-box rotatably mounted in bearings in the standards, a drag adapted to be used in connection with the core-box, a laterally-adjustable track located below the core-box and drag, a laterally-extensible skeleton truck mounted on the track, a platen arranged to travel upward and downward, through the truck, to receive the drag with its core and deposit them thereon, and means for operating such platen, substantially as described.

2. In combination, a main supporting-base A , a pair of vertical standards B laterally adjustable thereon, a core-box F rotatably mounted, by means of opposite trunnions F' , in bearings B^2 thereon, a drag G adapted to be used in connection with the core-box F , a laterally-adjustable track D located below said core-box and drag, a laterally-extensible skeleton truck, mounted on the track D , a platen C^3 arranged to travel upward and downward, through said truck, to receive said drag G with its core and deposit the same on said truck E , and means for operating said platen C^3 substantially as described.

In testimony whereof I have signed my name to this specification in the presence of two subscribing witnesses.

STANTON GRIFFITH.
